CLAIM

The ornamental design for an electronic device for musical instrument, as shown and described.

DESCRIPTION

FIG. 1 is a top view of the electronic device for musical instrument illustrating my new ornamental design;

FIG. 2 is a right-side view thereof, the left-side view being a mirror image of the right-side view;

FIG. 3 is a front view thereof; and,

FIG. 4 is a rear view thereof.

The broken lines in the figures show portions of the electronic device for musical instrument that form no part of the claimed design.
